UNITED STATES PATENT OFFICE

LEO J. GOLDBERG, OF HEWLETT, NEW YORK, ASSIGNOR TO LEONORA SILK UNDERWEAR COMPANY, INC., OF NEW YORK, N. Y., A CORPORATION OF NEW YORK

DESIGN FOR A NIGHTGOWN

Application filed December 10, 1932. Serial No. 46,426. Term of patent 3½ years.

To all whom it may concern:

Be it known that I, LEO J. GOLDBERG, a citizen of the United States, and resident of Hewlett, Long Island, in the county of Nassau and State of New York, have invented a new, original, and ornamental Design for a Nightgown, of which the following is a specification, reference being had to the accompanying drawing, forming part thereof.

I claim:

The ornamental design for a nightgown substantially as shown.

LEO J. GOLDBERG.
